UNITED STATES PATENT OFFICE.

FRANK E. WELLMAN, OF KANSAS CITY, KANSAS, ASSIGNOR TO THE KANSAS CITY GASOLINE COMPANY, OF KANSAS CITY, KANSAS, A CORPORATION OF KANSAS.

APPARATUS FOR AND METHOD OF CRACKING HYDROCARBONS.

Application filed April 21, 1920. Serial No. 375,513.

To all whom it may concern:

Be it known that I, FRANK E. WELLMAN, a citizen of the United States, residing at Kansas City, in the county of Wyandotte and State of Kansas, have invented certain new and useful Improvements in Apparatus for and Methods of Cracking Hydrocarbons, of which the following is a specification, reference being had therein to the accompanying drawing.

My invention relates to the reduction of hydrocarbons from those having a high boiling point to those having lower boiling points by what is known as "cracking," under heat and pressure.

My invention has for its object to facilitate the operation heretofore described and claimed in my prior copending application Serial Number 306,321, filed June 24, 1919, patented December 14, 1920, No. 1,362,160. Broadly stated, I attain my present object, with ancillary objects which will sufficiently appear from the detailed description, by providing cracking tubes in a furnace, and causing a rapid circulation of oil (hydrocarbons) through said cracking tubes, then passing the same through a long container sufficiently large to slacken the speed of the flowing liquid enough to allow the carbon to settle out, after which the oil is picked up again and put through the same cycle, fresh oil being charged in from time to time at an intermediate point between the settling tubes and the cracking tubes on that side of the settling tubes through which the current of oil is toward the cracking tubes.

My invention is illustrated as to one embodiment in the accompanying drawings in which:

Fig. 1 is a longitudinal sectional view of a furnace showing cracking tubes therein in full lines, settling tubes connected therewith partly in full and partly in dotted lines, together with the connected parts;

Fig. 2 is a front view of the furnace and external parts with a wall of the furnace separating the cracking tubes from the settling tubes, shown in dotted lines; and

Fig. 3 is a diagram or isometric projection, showing the system of tubes complete, removed entirely from the furnace.

Referring to the drawings, 1 indicates the charging line, 2 is the housing of a suitable pump, which may be of any suitable type, as for example a helical turbine or cen-

trifugal pump. The direction in which the oil passes through the pump is indicated by the arrows in all the figures. 3 is the discharge line from the pump leading to a manifold 4 from which rise distributing pipes 5 which are each equipped with clean-out flanges. These distributing pipes are of such size that their total cross-sectional area is less than the capacity of the pump, when filled, or in other words the pump 2 has an over-capacity relatively to the distributing pipes 5. This insures an even distribution to all of said pipes, since no one of them can rob the others. 6 indicates the outer ends of the upper sections of the cracking tubes. The oil is discharged down through the distributing pipes 5 into the base of the fractionators, and flows thence down through the sections 7 of the cracking tubes through the whole length of the furnace, at the far end of which these tubes are vertically connected through welded standpipes with the lower cracking sections 8. Passing from the upper section 7 into these lower sections 8, the oil again flows forwardly through the length of the furnace to the header or manifold 9 from which it falls into the pipe 10 through the drop connection 11. The pipe 10 connects into the front end of a large settling tube 12, which extends to the far end of the furnace, and through a welded cross-connection 12^a to the rear end of tube 13, similar to 12, through which the oil again flows forward to the front end of the furnace, then through the drop tube 14 to the pump 2.

The distributing pipes connect in to the base of the risers 16 of the fractionator. This is for convenience only as of course distribution might be made separately to the pipes 7. This fractionator is composed of a grid of relatively small pipes at its upper end, united by a header common to all of them, from which is taken off a dome pipe carrying the vapor line 17 commonly called the "draw-off line," and two pressure gauge lines 18. I also provide a steam line marked 19 and a blow-out pipe marked 20, with valves 19^a for the steam line.

The operation of this apparatus will be sufficiently understood from the foregoing description with very few additional explanations. My present apparatus has the settling tubes 12 and 13 of eight inch diameter, while the cracking tubes 7 and 8

are three and one-half inches inside diameter, and approximately thirty-five feet long. The settling tubes are level, while the cracking tubes have a total drop or slope of twelve inches, that is to say six inches drop of the upper tubes from the front to back of the furnace, and six inches drop of the lower tubes from back to front of the furnace. I have shown all these tubes with their ends 10 projecting out of the furnace and equipped with detachable heads for cleaning out. These heads are shown secured by bolts each extended for a considerable distance along the pipe, and welded thereto throughout its length. Of course the number of fractionator tubes can be increased or diminished as necessity dictates, but in the completed machine I have as many risers as there are 15 horizontal units in the furnace.

20 The difference in diameter and thereby reduced capacity of the cracking tubes and the settling pipes allows for a much slower movement of the cracked liquid in the settling pipes to allow precipitation of carbon which is removed at convenient intervals through the blow-out line 20, and if desired the whole system of pipes scoured at the same time by steam from the steam line 19, all of which is fully described and 25 claimed in my previous application herein-before referred to.

It may be added that we charge this apparatus with one half the cubical contents. This is brought up to the 300 lb. pressure, 35 50% is drawn off as vapors and the remainder is quickly blown out. The operation is then repeated. This epitomizes the operation only, and is not to be construed as a limitation. Continuous operation is also 40 within the scope of my invention, as described, the intervals of time between the blowing off being lengthened as circumstances require.

What I claim is:—

45 1. Apparatus of the class described comprising cracking tubes and settling tubes connected in a continuous coil or series, said cracking tubes being exposed to cracking temperature, and being of smaller diameter 50 and capacity than the settling tubes, means for producing a circulation of hydrocarbons

to be cracked rapidly through the cracking tubes, slowly from them through the larger settling tubes and then again through the cracking tubes, said tubes being arranged to 55 form a constant downward channel for the hydrocarbon from the entrance to the cracking tubes to the discharge point of the settling tubes, and means for blowing out 60 said settling tubes between operations. 65

2. Apparatus of the class described comprising cracking tubes and settling tubes connected in a continuous coil or series, said cracking tubes being exposed to cracking temperature, and being of smaller diameter 70 and capacity than the settling tubes, means for producing a circulation of hydrocarbons to be cracked rapidly through the cracking tubes, slowly from them through the larger settling tubes, to allow the carbon to settle 75 out, and then again rapidly through the cracking tubes, the said cracking tubes being in parallel with each other, and distributing tubes equal in number and individually connected to the cracking tubes, said circulating means being in the form of a feed pump having a capacity greater than the aggregate capacity of all the distributing pipes, and means for feeding oil to said pump in sufficient volume to maintain equal distribution. 80

3. The method of cracking hydrocarbons which consists in maintaining rapid circulation of the same through a constricted area heated to cracking temperature, then causing the same to expand into a less constricted area for settling purposes, then picking up the material from which the carbon has settled out, and returning it to the constricted cracking area, taking off cracked products from the constricted area and finally when the required percentage of conversion is attained blowing out the contents of the settling area. 85 90 95

4. The method of cracking hydrocarbons as claimed in claim 3 with the additional step of adding fresh oil in advance of the constricted area, thus maintaining the volume of circulation against losses.

In testimony whereof I affix my signature.

FRANK E. WELLMAN.
